CLAIM

The ornamental design for a refrigerated display counter, as shown and described.

DESCRIPTION

FIG. 1 is a perspective view of a refrigerated display counter showing my new design;

FIG. 2 is a front view thereof;

FIG. 3 is a rear view thereof;

FIG. 4 is a right side view thereof, a left side view being a mirror image of the right side view; and,

FIG. 5 is a top view thereof, a bottom view being omitted since it is featureless and invisible in normal use.

(Continued)

The broken lines shown in the drawings illustrate portions of the refrigerated display counter that form no part of the claimed design.
